UNITED STATES PATENT OFFICE.

HENRY W. FISHER, OF BRIDGEPORT, CONNECTICUT.

COMBINED GREASE AND OIL GUN.

1,319,523.

Specification of Letters Patent.

Patented Oct. 21, 1919.

Application filed August 19, 1918. Serial No. 250,449.

To all whom it may concern:

Be it known that I, HENRY W. FISHER, a citizen of the United States, and resident of Bridgeport, in the county of Fairfield and State of Connecticut, have invented certain new and useful Improvements in Combined Grease and Oil Guns, of which the following is a specification.

My invention relates to improvements in combined grease and oil guns such as are employed for oiling and greasing automobile transmissions, bearings and other operative parts.

The purpose of the invention is to improve upon implements of the above character and particularly to improve upon grease guns of the type shown in my prior Patent #1,165,083, by providing a gun, the nozzle of which may be adjusted at an angle with respect to the barrel of the gun so that the gun may be more conveniently and safely handled in oiling certain parts of a machine. Further to provide an improved construction whereby the grease chamber of the gun may be conveniently and quickly opened and closed for the purpose of filling the gun with grease.

With these and other objects in view the invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings, forming a part of this specification, and upon which,

Figure 1 shows a side elevation of my improved construction of grease gun, the nozzle of which is shown adjusted at an angle with respect to the cylinder of the gun.

Fig. 2 shows a central vertical longitudinal section of the gun construction shown in Fig. 1.

Fig. 3 is a detached view of the removable end portion of the gun shown in Figs. 1 and 2.

Fig. 4 is a detached view of the end portion of the body shown in Fig. 1 and as

viewed from the top thereof, the adjustable coupling being removed.

Fig. 5 is an end view of the end of the body shown in Fig. 4 with nut and nipple 60 removed.

Fig. 6 is a vertical longitudinal section of the end portion shown in Fig. 4.

Fig. 7 is a detached side view of the adjustable clip shown in Figs. 1, 2, 3 and 8, 65 for locking the removable end portion of the gun in position, and

Fig. 8 shows a detached side view of the removable cover portion of the grease gun, the intermediate tubular portion of which 70 has been omitted, which is somewhat preferable for handling oils.

Fig. 9 shows an attached cross sectional view of the adjustable nipple shown in Figs. 2 and 6.

Referring now in detail to the reference characters shown upon the drawings 10 denotes the cylindrical body, the forward end portion 11 of which is rounded and provided with a slot 12 through which the adjustable 80 nipple 13 is operatively fitted. The upper end portion of this cylindrical reservoir is inclosed by the tubular cover 14 which is provided with an internal tubular extension 15 that fits into the cylindrical body 85 and is also provided with a flange 16 that covers the outer portion of the cylinder adjacent to the said open end portion. The piston rod 17 which is provided with an operating handle 18 is slidably mounted in this 90 inclosing cover and upon the inner end of the rod is mounted the plunger 19 adapted to be drawn back and forth by the rod and handle. From this construction it will be seen that the two cylindrical portions of the 95 body of the gun are snugly closed together, one within the other. In this connection it will also be noted that the outer cylindrical part is provided upon its face with a pin 20 that fits into a slot 21, when the parts are 100 closed together, and it is further engaged by the slot 22 of the adjustable sheet metal collar 23 mounted upon the outer surface of the flange 16 and held against sidewise movement by the lugs 24 formed upon the flange. 105 This collar is obviously adapted to be annularly adjusted for the purpose of engaging and disengaging the pin 20 to lock the parts together, thereby releasing the same for removal and refilling.

Referring again to the forward end of the gun it will be noted that I provide a flexible

2
 washer 25 inside of the rounded end portion of the barrel having opposite sides between shoulders 30 formed by it and the flange of the adjustable nipple 13. The inner head portion of this nipple is elongated having opposite flattened sides 31 which are guided between the shoulders 30 formed by the contracted or flattened sides 26-26 of this end portion of the body, leaving the outwardly extended end portion of the nipple free to be moved backward and forward within the slot 12. A central hole is provided through this nipple to allow the grease to be properly forced out therefrom. A nut 27 is fitted upon the outer threaded portion of the nipple to firmly draw the inner head portion up against the bushing of the cylinder to form a tight connection.

28 refers to a coupling that is detachably mounted upon the said nipple and 29 is a pipe which may be any suitable length to form a further extension as may be required.

As before suggested the gun is adapted to be used both as a grease gun and an oil gun and when used for the handling of grease the gun is loaded by removing the cover and filling the gun from that end. On the other hand if it is to be used as an oiler the nozzle is simply submerged in the oil and the plunger drawn back so as to suck the oil up into the gun in the usual and well known manner.

Having thus described my invention, what I claim and desire to secure by Letters Patent is,

1. In a grease gun of the class described, the combination of a cylindrical body having an integral rounded end portion, the two opposite sides of which are flattened forming shoulders and provided with a slot between the said shoulders, an adjustable nipple positioned in the slot including a threaded por-

tion and an integral head, the two sides of which are flattened and positioned against the shoulders to prevent turning, the engaging face of said head being rounded to conform to the shape of the inner wall of the end of the cylindrical body, a flexible washer fitted between the rounded portion of the head of the nipple and the inner wall of the end of the body, a nut mounted upon the outer threaded portion of the nipple and fitted against the end of the body, and a plunger mounted in the cylindrical body and adapted to force the contents of the cylinder out through the nipple.

2. In a grease gun of the class described, the combination of a cylindrical body having one open end and an integral rounded end portion whose two opposite sides are flattened to form shoulders and a slot between the said shoulders, an adjustable nipple positioned in the slot including a threaded portion and an integral elongated head with opposite flattened side portions positioned against the shoulders to prevent turning, and having a rounded engaging face to conform to the shape of the inner wall of the end of the body, a nut mounted upon the outer threaded portion of the nipple and fitted against the end of the body, a cover for the open end, means for securing the cover to the body, and a piston and plunger mounted in the cover and cylindrical body and adapted to force the contents of the cylinder out through the nipple.

Signed at Bridgeport in the county of Fairfield and State of Connecticut this 17th day of August A. D., 1918.

HENRY W. FISHER.
